ELECTROPNEUMATIC BRAKE

Filed May 27, 1926

UNITED STATES PATENT OFFICE.

CLYDE C. FARMER, OF PITTSBURGH, AND JOSEPH C. MCCUNE, OF EDGEWOOD, PENNSYLVANIA, ASSIGNORS TO THE WESTINGHOUSE AIR BRAKE COMPANY, OF WILMINGTON, PENNSYLVANIA, A CORPORATION OF PENNSYLVANIA.

ELECTROPNEUMATIC BRAKE.

Application filed May 27, 1926. Serial No. 111,995.

This invention relates to safety car control equipments, and the principal object of our invention is to provide an improved and simplified electro-pneumatic safety car control equipment.

In the accompanying drawing, the single figure is a diagrammatic view of a safety car control equipment embodying our invention.

As shown in the drawing, the equipment may comprise a brake switch at each end of the car having the operating positions designated as release, lap, and service, and a foot controlled switch device at each end of the car comprising a push button 1 and a switch member 2 adapted to be operated by said button.

The equipment also includes an emergency valve device 3, a brake cylinder 4, a main reservoir 5, a release magnet 6, a service magnet 7, an emergency magnet 8, a cut-off switch device 9, and a holding coil controlling switch device 10.

The emergency valve device 3 comprises a casing having a piston chamber 11 connected to a control pipe 12 and containing a piston 13 and a valve chamber 14 connected to the main reservoir 5 through pipe 15 and containing a slide valve 16 adapted to be operated by piston 13.

In operation, with the push button 1 held depressed, the switch member 2 closes a circuit from a current supply wire 17 to a wire 18 which is connected to the emergency magnet 8. Said magnet is thereby energized and operates double beat valves 19 and 20, so that valve 19 is seated, cutting off communication from control pipe 12 to an atmospheric exhaust port 21, and valve 20 is unseated, permitting fluid under pressure to be supplied from the main reservoir pipe 15, through a restricted port 22, to the control pipe 12. Piston chamber 11 being thus charged with fluid at main reservoir pressure and the valve chamber 14 being connected to the main reservoir, the piston 13 will be shifted to normal release position, due to the differential in pressure which is created by the small piston 23 being constantly subject to atmospheric pressure.

With the brake switch in release position, the current supply wire 17 is connected to

wire 24, which leads to release magnet 6, so that said magnet is energized and operates to hold the release valve 25 unseated. The application magnet 7 is deenergized, and the valve 26 is therefore permitted to seat. The release valve 25 being open, the brake cylinder 4 is connected to the exhaust, through pipe 27, passage 28, cavity 29 in emergency slide valve 16, passage 30, pipe 31, and past valve 25 to exhaust port 32.

The cut-off switch device 9 comprises a casing containing a piston 33, connected on one side to a pipe 34, leading to pipe 31 and said piston is provided with a stem 35 carrying a contact member 36 adapted to control a circuit from current supply wire 17 to emergency magnet wire 18.

When, as in release position, there is no fluid under pressure in the brake cylinder, the piston 33 will be held in its lower position by spring 37, so that the circuit from wire 17 to wire 18 is opened.

The holding coil controlling switch device 10 comprises a casing containing a piston 38 subject to the pressure in the control pipe 12 and having a stem 39 carrying a switch member 40. When the control pipe is charged with fluid under pressure, the piston 38 is forced to its upper position, in which the switch member 40 closes a circuit to a holding coil (not shown) which maintains the power circuit.

An application of the brakes may be effected by moving the brake switch to service application position, in which the current supply wire 17 is connected to wire 41, which leads to the application magnet 7. Said magnet being thus energized, the valve 26 is unseated and fluid under pressure is vented from one side of a relay valve 42 through passage 43, past valve 26 to passage 44, which is open to the brake cylinder 4. The relay valve 42 is then moved upwardly by fluid at main reservoir pressure acting on the outer lower area of said valve and thereby the main reservoir pipe 45 is connected to passage 44, so that fluid from the main reservoir is supplied to the brake cylinder through pipe 31, cavity 29 in slide valve 16, passage 28, and pipe 27. The release magnet 6 is deenergized in the service application po-

sition of the brake switch, so that the valve 25 is permitted to seat and prevent the escape of fluid from the brake cylinder.

When a service application of the brakes 5 is effected, fluid under pressure is supplied from the pipe 31, through pipe 34 to cut-off switch piston 33, and if the brake cylinder pressure be increased to a predetermined amount, said piston will be shifted upwardly 10 to cause the switch member 36 to close a circuit from supply wire 17 to emergency magnet wire 18.

It will thus be evident, that if a service application of the brakes is effected, the foot 15 button 1 may be released without causing the emergency magnet 8 to be deenergized.

If the brakes are not applied and the motorman should release the foot button 1, either accidentally or by design, the circuit 20 of the emergency magnet 8 will be opened, permitting the double beat valve 20 to seat and the valve 19 to unseat. The unseating of valve 19 permits fluid under pressure from the control pipe 12 to be vented to the 25 exhaust port 21 and the reduction in control pipe pressure thus produced, causes the emergency piston 13 to be shifted to its outer position by fluid under pressure in valve chamber 14. The slide valve 16 is thus 30 moved to emergency position, in which passage 28 is opened to valve chamber 14, permitting fluid under pressure to flow from said valve chamber and consequently the main reservoir 5 to the brake cylinder 4, so 35 as to cause an emergency application of the brakes.

The venting of fluid from the control pipe 12 also reduces the pressure on piston 38, permitting spring 46 to shift the piston 38 40 to its lower position and thereby causing the switch member 40 to open the circuit of the holding coil. The holding coil being thus deenergized, the power circuit is opened.

45 The brakes may be released after an emergency application of the brakes, by depressing the foot button 1, whereby the emergency magnet 8 is again energized, so as to effect the closure of valve 19 and the opening of valve 20. Fluid under pressure is then supplied from the main reservoir to the control pipe 12 and the emergency piston 13 is returned to release position, in 50 which the brake cylinder 4 is connected to the atmosphere, as hereinbefore explained.

55 The piston 38 is also moved upwardly by fluid under pressure in the control pipe 12, so as to close the circuit to the holding coil and thus effect the closing of the power circuit.

60 When the motorman goes from one end of the car to the other, he can prevent an emergency application of the brakes upon release of the push button 1, if he makes a 65 service application of the brakes of a pre-

determined amount, and when he is at the other end of the car he can release the brakes by pressing down the push button 1, so as to close the circuit to the emergency magnet 8 and by moving the brake switch to release position. The brakes will then be released, as hereinbefore described.

A conductor's valve 47 connected to the control pipe 12 may be installed in the cab, so that the motorman may operate said valve 70 to vent air from the control pipe to effect an emergency application of the brakes, in case of possible failure of the electric control. A similar conductor's valve 48 may be provided for control by the conductor, 75 in case the conductor or a passenger should find it necessary to effect an emergency application of the brakes.

Having now described our invention, what we claim as new and desire to secure 80 by Letters Patent, is:—

1. In a safety control equipment, the combination with a control pipe and an emergency valve device operated upon a reduction in fluid pressure in said pipe for effecting an application of the brakes, of a valve 90 for venting fluid from said pipe, a magnet for operating said valve, a foot controlled switch for controlling the circuit of said magnet, and a switch device operated upon an application of the brakes for controlling the circuit of said magnet.

2. In a safety control equipment, the combination with a control pipe and an emergency valve device operated upon a reduction in fluid pressure in said pipe for effecting an application of the brakes, of a valve 100 for venting fluid from said pipe, a magnet adapted upon deenergization to open said valve, a foot controlled switch operative upon release for opening the circuit of said magnet, and a switch device operated upon applying the brakes for closing the circuit to said magnet.

3. In a safety control equipment, the combination with a control pipe and an emergency valve device operated upon a reduction in fluid pressure in said pipe for effecting an application of the brakes, of a valve 110 for venting fluid from said pipe, a valve for supplying fluid under pressure to said pipe, and a magnet for operating said valves.

4. In a safety control equipment, the combination with a brake cylinder, a control 120 pipe, and a valve device operated upon a reduction in fluid pressure in said pipe for effecting an emergency application of the brakes, of a valve for venting fluid from the control pipe, a magnet adapted upon deenergization for opening said valve, and a switch device operated upon a predetermined increase in pressure in the brake cylinder 125 for closing a circuit to energize said magnet.

5. In a safety control equipment, the combination with electrically controlled means for controlling the application of the brakes and a brake switch device for controlling said means, of a control pipe, means operated upon a reduction in pressure in said pipe for effecting an emergency application of the brakes, a valve for venting fluid from
- said pipe, a magnet for operating said valve, and a foot controlled switch for controlling the circuit of said magnet.

In testimony whereof we have hereunto set our hands.

CLYDE C. FARMER.
JOSEPH C. McCUNE.
